UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

DIVIDED LAST.

No. 901,918.

Specification of Letters Patent.

Patented Oct. 20, 1908.

Application filed March 16, 1908. Serial No. 421,521

To all whom it may concern:

Be it known that I, EDWIN O. KRENTLER, a citizen of the United States, residing at Detroit, in the county of Wayne and State of Michigan, have invented an Improvement in Divided Lasts, of which the following description, in connection with the accompanying drawings, is a specification, like letters on the drawings representing like parts.

The slide last and the swing last (types of which are shown in the Krentler last patents No. 603,790 and No. 764,894, and in the Gordon last patents No. 500,711, and No. 449,877) have each their respective advantages long recognized by the trade, the slide last being superior in some respects, especially as a follower or second last, but, because of various practical disadvantages of manufacture of the same and of use, it has never reached prominence commercially, and accordingly my present invention aims to combine the advantages of both of these types of last in one and the same last, while eliminating the disadvantages thereof.

Briefly stated my invention, in its broader aspect, resides in providing a divided last with means whereby the heel-part slides obliquely downwardly and rearwardly to lengthened position when being inserted in a shoe, but swings upwardly, as on a pivot, to shortened position when being removed from the shoe. The wedging or sliding downward movement permits the last to get into the shoe easily without danger of injuring the shoe lining or counter, whereas the swinging upward movement permits the heel-part of the last to get out of the shoe easily. The advantages of the sliding downward movement are well set forth in the Wright patent No. 666,726, and it will be readily understood without further explanation that the wedging or sliding movement gives the last easy entrance to the shoe, and inasmuch as the rear surface of the heel-part engages the lining or inner surface of the counter portion of the shoe with a direct outward thrust and substantially without any sliding or downward frictional pressure on the lining, there is an entire absence of any tendency to disturb or wrinkle the lining or to break the counter. But it is exceedingly difficult to get a sliding last out of the shoe. The last is then in inverted position on the jack spindle, and the ordinary way of get-

ting the heel-part of a last out of the shoe is to press downwardly on the toe part, thereby causing the jack spindle to exert sufficient twisting leverage on the heel-part to dislodge it from the shoe, as shown in the Barlow patent No. 568,326, but this movement or leverage has so little influence on a sliding heel-part that it is common for the operator not only to press down on the toe but also to press the heel part of the last downwardly by pressing on the heel and shank of the shoe, and this tends to strain and distort the shoe and to break the shank. And in such an obliquely severed last as the swing-heel last of Fitz 362,994, the last-parts are so jointed that the heel-part, in order to move to shortened position, must be lifted with the pressure towards the back. But by properly connecting the last-parts and dividing the heel-part from the fore-part along a line of severance which permits the last, when on the jack spindle as stated, to break and to allow its heel-part to partially slide and yet to swing about a pivot, upon applying downward pressure to the toe of the last and shoe, the heel-part of the last is removed readily and easily from the shoe and this is accomplished without the slightest straining or tendency to injure the shoe, and especially without any liability of breaking its shank.

To make the broad nature of my invention clearer, I will refer to two other patents, viz. Tyler, No. 601,621, and Trufant, No. 633,741. In said Tyler construction the heel-part has the swinging movement and the line of severance is so sloping and oblique that the heel-part may almost be said to slide, but as the heel-part is immovably secured to the hinge-plate so that it has no pivotal movement except about the forepart pivot, the result is that the rear surface of the heel-part of the last can only enter the heel-part of the shoe by a downward movement over the shoe lining and counter, and cannot engage the latter by the direct outward thrust above explained, and moreover, in order to get even the gradual swinging movement of the Tyler patent, it is necessary to place the hinge pivot far forward towards the toe and near the bottom. Trufant (and this is equally true of Cole, No. 543,375) on the other hand, although disclosing a construction in which the heel-part is capable of both a swinging and a sliding movement, does not disclose in

any way my invention, inasmuch as the swinging of the heel-part can only take place after it has escaped from the shoe, i. e., the heel-part must slide down into the shoe and 5 must also slide up out of the shoe, the lines of cut being such that, when the last is in lengthened position in the shoe, there is no capability of breaking the last by the leverage of the jack-spindle by giving the heel- 10 part a swinging movement, as about a pivot, in order to get it out of the shoe, and hence there is the same difficulty in getting the last out of the shoe as before.

Further advantages of my invention will 15 be pointed out in the course of the following description of the preferred constructional details, taken with reference to the accompanying drawings, in which one of the preferred embodiments of the invention is 20 shown in the drawings.

In the drawings, Figure 1 is a view in side elevation of a last constructed according to my invention, the side being broken out for clearness of illustration; Fig. 2 shows the 25 last in side elevation in operative position on a jack, being removed from a shoe; Fig. 3 is a side elevation of a modified construction; Figs. 4 and 5 show respectively in bottom plan and section a detail of the alining means 30 for preventing the last from shifting; Figs. 6 and 7 are details of the link hinge or joint connection.

In carrying out my invention it is essential that the forepart 1 and heel-part 2, as 35 already stated, shall be so severed, or provided with such shaped abutting ends, that two distinct movements can take place, first, for insertion into a shoe, the heel-part can slide rearwardly down into the shoe so as to bring the back of the heel-part against the shoe lining and counter with a straight-rearward or straight-out thrust as distinguished 40 from a swinging lining-scraping movement, and, second, for removal from a shoe, the heel-part can be turned with more or less swinging movement, out of the shoe by the 45 prying exertion of the jack spindle. This gives easy entrance to the last without injury to the shoe, lining or counter, and likewise 50 easy removal without injury to the shoe shank or upper.

Referring now to the drawings, in my preferred construction, Figs. 1 and 2, it will be seen that the rear end of the forepart 1 is 55 provided with a gentle sloping oblique wall 3 which terminates at the point 4 and a steeper sloping oblique wall 5 extending from the point 4 preferably to the bottom of the last at 6, and the heel-part 2 has a comparatively 60 steep oblique wall 7 at the same angle as the wall 5 and fitting against the same from approximately the point 4, and preferably extending more or less above the same as indicated at 8, to the point 6, the forward upper 65 end of the heel-part from the point 8 being

preferably cut away as shown at 9 so as not to interfere with the instep or laced portion of the shoe when the last is being inserted or removed from the latter. The two last-parts 1 and 2 are shown as permanently connected 70 by a link or hinge plate 10, to the opposite ends of which the respective last parts are freely pivoted by pins 11 and 12 respectively. The pivots and link are so located that when the last parts are in lengthened position as 75 shown in full lines Fig. 1, the two end walls 5 and 7 are held tightly flat against each other and the bottom line of the last maintained in unbroken alinement at the point 6, but when the inverted heel-part is engaged by a jack pin 13, as shown in Fig. 2, and a downward pressure is applied to the toe of the last, the heel-part can swing and slide on the point 4 as a fulcrum, pivoting 80 not only on the pin 11 but also on the pin 12 85 so as to get the benefit of a compound sliding and swinging movement away from the lining and counter of the shoe. The upper front end of the heel-part must of course be separated from the wall or face 3 by a sufficient gap to permit the swinging movement mentioned and while it is not necessary that this gap shall have the extent shown between the faces 3 and 8, it must be substantially 90 equal to the angle between the face 3 and a 95 continuation or projection of the face 7 (as shown in the dotted line position *a* of the heel-part).

In my preferred and most complete construction, I prefer that the heel-part shall 100 be permitted to have an actual sliding engagement with the forepart both in going into the shoe and in drawing out of the shoe, and to this end I provide a slotted link, the slot being preferably at the heel end of the 105 link as indicated at 14, although by reversing said link so that said slot comes in the forepart much the same result is effected. If desired, the link may be provided with opposite slots as shown at 15, 16, Fig. 7. 110 The idea is to permit the two pivots 11 and 12 to approach each other at times or in other words to permit the downward-slide and the upward-slide-swing of the heel-part with relation to the forepart, and it will be 115 understood that I do not restrict myself to a slotted link as the means of permitting the movement as it can be secured in various ways, and I make no claim to the slotted link *per se*, as that is not new (see patent of 120 Clark, No. 534,856). As a single link connection would not alone afford sufficient resistance against twisting strains, I provide 125 coöoperating means for rendering the last steady and firm against lateral shifting, twisting and like strains, said means being herein shown as a groove 17 in the bottom end or corner of the forepart, and a projection or pin 18 projecting from the front lower end of the heel-part to fit said groove 130

or recess 17 when the last parts are in lengthened position.

In Fig. 3 I have shown one of many possible modifications, this construction however being less efficient than that already described. Instead of forming the intervening gap between the upper secant ends of the forepart and heel-part by cutting away the upper end of the forepart at an angle to the lower end wall of the forepart, I have shown the rear end of the forepart as provided with a single oblique secant wall 19 extending from the crown of the last straight down to the bottom, the upper forward portion of the heel-part being cut away at 20 from an intermediate point 21 so positioned with relation to the connecting means or link 10 as to permit the heel-part to be turned with a swinging movement on the point 21 as a fulcrum for disengaging the heel-part from the counter portion of the shoe in the process of removal. Below the point 21 the heel-part has an oblique surface 22 the same as the surface 7 of the previously described construction. The wall 20 must be sufficiently long so as to bring the point 21 toward the bottom of the last a sufficient distance to cause the heel-part to swing upwardly without any lengthening movement, and it will readily be understood that this point will depend also to some extent upon the angle or obliquity of the diagonal line of cut 19. The gap between the upper portions of the forepart and heel-part, permits in each instance the desired initial pivoting or swinging of the heel-part for removal from the shoe and yet the oblique lines of cut permit the desired sliding movement for entrance into the shoe, the last parts in each instance being connected by such means as will not interfere with these desired movements.

As already stated, my invention is capable of a wide range of varieties of cuts, and connections, the only essential, so far as concerns my invention in its broadest aspects, being that the two features of lines of severance and connecting means shall be combined as to permit an inward sliding movement in a downward rearward direction for insertion in a shoe, and an outward swinging or combined swinging and sliding movement for withdrawal from a shoe. For instance, in the Fitz patent No. 817,966, notwithstanding the lines of severance, the two connecting links or members are so positioned and pivoted that the last cannot slide into the shoe and swing out of the shoe, but on the contrary is compelled to move in both directions along exactly the same line of swinging movement.

In use, in pulling the shoe off the last all that is necessary to do with this last is to bend the toe down and the forepart will move on the heel-part in a manner quite

similar to an ordinary hinged last, but preferably with the addition of some sliding movement, especially in the construction of Figs. 1 and 2, and the slanting portion 3 then permits the heel-part to slip under the forepart with a continuation of said swinging or hinging movement. The leather of the shoe maintains a steady pressure on the last when in the shoe, and in pulling the last out of the shoe this pressure tends to hold the heel-part against the forepart, thereby giving just the requisite additional shortening movement to the last necessary to prevent absolutely all tendency of breaking the shank of the shoe and straining the upper (which disasters are common with regular hinged lasts) and yet, because of the location of the angle 4, Figs. 1 and 2, and the angle 21, Fig. 3, with reference to the connection 10, or, rather because of the mutual arrangement of the joint connections and the angular cut including the walls 5, 7 and 3, Figs. 1 and 2, and the walls 19, 20 and 22 Fig. 3, the heel-part, when subjected to the prying action of the post 13 of the jack, tends to fulcrum on the annular point 4, Figs. 1 and 2, or 21 Fig. 3, and thereby get an initial swinging movement out of the heel of the shoe. As, however, there is only one controlling link or connection 10, and this connection is of such a nature that it permits the heel-part to keep in contact with the forepart as well as to pivot freely at 12, this swinging movement is accompanied by a sliding movement, the surface 7 sliding along or over the corner 4 until the corner 8 engages the surface 3, Figs. 1 and 2, as the surface 7 gets into longitudinal alinement with said surface 3, whereupon the subsequent shortening movement is thereafter mainly a sliding movement of the surface 7 along the surface 3. This swinging movement or capacity of the heel-part to yield readily to the prying action of the jack spindle 13 when the toe of the shoe is pressed downwardly, makes it extremely easy to remove the last from the shoe and because of this ease of removal all the previous liability of injuring the shoe as above explained, is eliminated. On the other hand, when the last is to be inserted in the shoe, my construction enables it to get all the recognized advantages of the regular slide last. The forepart 1 is first inserted into the forepart of the shoe in usual manner, and then the heel-part is turned into the dotted line position *a*, Fig. 1; with the surface 7 alining with the surface 5, whereupon the heel-part is shoved downward into place simply by vertical pressure, the surface 7 sliding directly on the surface 5, with the result that the heel-part engages the lining and counter of the shoe with an outward pressure as distinguished from a downward-sliding pressure. In the usual hinged last, where

4

the rear end of the heel-part is obliged to turn down with a swinging movement along the path of an arc about the hinge pintle or pivot as a center, the bottom rear corner of the heel-part is very apt to break down the top edge of the counter, especially in oxford or low-cuts, so that it is usually necessary to use a shoe horn or spoon to permit the heel-part to get started into the shoe, which strains the leather and consumes time and patience. By my construction, in which the heel-part is not obliged to enter the shoe by any such swinging movement, this danger of breaking down the top edge of the shoe at the counter is not present because the last is so short when it enters the shoe that it escapes engagement with the top of the counter altogether when being inserted, and the bottom edge of the heel-part is entirely within the shoe before it can come into engagement with the counter portion of the shoe at all. This will be evident viewing the dotted line position *a*, Fig. 1. The dotted line position *b*, Fig. 1, shows the position into which the heel-part is swung from its full line position for removal from a shoe, and *c* indicates the position which the heel-part finally assumes when fully collapsed.

A further important feature of my construction, which is of decided value, especially in a follower last, irrespective of whether the link is slotted or not, resides in providing the forepart with the two oblique walls 3, 5, and the heel-part with the cooperating oblique wall 7, at an angle to each other, and connecting the heel-part by such form of connecting means that it permits the automatic turning or adjustment of the heel-part so as to bring its oblique wall into flat abutting contact against the lower of said two oblique walls of the forepart when the last is in lengthened position and into flat abutting contact against the upper of said two oblique walls of the forepart when the last is in shortened position, said construction effecting said cooperation of the parts in such a manner that the relasting thrusts or pressures are resisted by the direct mutual support of the walls 7, 3, the connecting means being of such a nature and so located that it does not tend to prevent this result but rather cooperates in aiding it. I do not mean to restrict myself to a technical link for accomplishing this, but wish to point out that the above mentioned tendency to remain in stable position is essential to this part of my invention irrespective of whatever kind of connecting means is employed. Also while I prefer to continue the inclined walls 3, 7, to the bottom of the last, this is not essential, so far as concerns this particular feature of my invention. When a shoe is being relasted, *i. e.*, is being forced back onto the last, the heel-part of the last is in the position indicated by the dotted line *c*, Fig. 1, excepting that the last is inverted and the heel-part is supported on the jack spindle 13. One of the great practical drawbacks to most lasts is that, in relasting, when the last, as stated, is on a jack with its bottom side up in position 70 for the operator to push the shoe onto the last, the forepart of the last will not remain in shortened position but will slide or swing back into lengthened position, under the slight downward pressure which most operators almost invariably use in connection with the forward main shoving pressure exerted on the shoe as it is pushed over the toe of the last toward the heel. The coöperating broad flat surfaces or faces 3, 7, of the forepart and 86 heel-part adjacent the crown of the last, and the relation of the connecting member thereto, which permits said faces automatically to adjust themselves to each other, overcomes this difficulty, so that the last invariably remains shortened, without requiring any special locks, hinges, or other cumbersome or expensive parts. I intend herein to claim this feature broadly.

The last-mentioned feature relates primarily to the last when used as a follower, but the main feature of my invention is equally effective for either a first-last or follower. In this I aim to accomplish for the heel-part what the last of the Pym patent 95 673,889 accomplished for the forepart, *viz.*, giving easy entrance and exit of the last to and from the shoe, but, while thus accomplishing the straight outward thrust against the lining when the last is put into the shoe, 100 I provide a swinging movement for easy removal. In carrying out my invention I prefer to employ materials and means already at hand, rearranging and combining the same, however, to accomplish the new results 105 above explained, and accordingly it will be understood that I make no claim to the link hinge (old in various patents, as for instance Clark 524,856 and Gedding 674,085) nor to a construction permitting a sliding movement 110 alone (old since Noyes No. 31,738) nor to a construction permitting a swinging movement alone.

Having described my invention, what I claim as new and desire to secure by Letters 115 Patent of the United States is,

1. In a divided last, the combination of a heel-part and forepart severed from each other by a line of cut affording a secant angle capable of permitting the heel-part 120 when in the shoe to slide downwardly and rearwardly in substantial parallelism to itself at all points for engaging the counter portion of a shoe, and to swing upwardly for leaving the counter portion of the shoe, 125 and connecting means for said two last-parts.
2. In a divided last, the combination of a heel-part and forepart severed from each other by a line of cut affording a secant 130

angle capable of permitting the heel-part when in the shoe to slide downwardly and rearwardly in substantial parallelism to itself at all points for engaging the counter portion of a shoe, and to swing upwardly for leaving the counter portion of the shoe, connecting means for said two last-parts, and means for maintaining the last-parts in alignment against lateral shifting.

10 3. The combination, in a divided last, of a forepart and heel-part separated at their upper portions by an intervening gap and thence separated along a line of cut extending obliquely downwardly and continuously 15 rearward at every succeeding lower point to the bottom of the last from the bottom of said gap, which bottom coincides with a point located at a distance from the bottom of the last permitting the heel-part when in 20 fully lengthened position in a shoe to have an initial swinging collapsing movement, without lengthening, about said point as a center, and connecting means arranged to coöperate with the uninterrupted rearward 25 oblique line of severance in permitting the heel-part to have final sliding movement in substantial parallelism to itself back into fully lengthened position in the shoe.

4. In a divided last, a forepart and heel-part, having angular secant faces at their meeting ends with level, uninterrupted surfaces permitting said last-parts to slide on each other in going to lengthened position, and the angle being located about midway 35 from bottom to top of the last and constituting the pivotal center for the heel-part to turn on in its upward swinging movement, and connecting means having a length which limits said downward movement to fully 40 lengthened position, the secant ends and connecting means being constructed and operating to permit the heel-part to have a combined swinging and sliding collapsing movement when in a shoe, and to permit said heel-part to have, when in the shoe, an obliquely 45 downward and rearward continuously-sliding lengthening movement to fully extended position against the counter of the shoe, whereby the back and front of said heel-part move down with substantially the same speed to the end of the lengthening movement.

5. In a divided last, the combination with a forepart and heel-part, of a link connection pivoted at its opposite ends in the respective last-parts, the forepart having at its rear end a wall extending rearwardly and downwardly in a single uninterrupted oblique plane throughout the entire extent 50 of the surface over which the heel-part slides, and the heel-part having a complementary abutting surface, all constructed and arranged to permit the heel-part to slide downward on and in continuous contact at all 55 points with said plane forepart wall, when

the last is in a shoe, until the heel-part is in fully lengthened position, the upper end of one of said last-parts being cut away at an angle to said wall from a point located at a distance from the bottom of the last 70 permitting the heel-part to disengage from the counter of the shoe by a shortening swinging movement and said connection being located at such a height and position in the last with reference to said point as to 75 permit said shortening swinging movement without interfering with said sliding lengthening movement.

6. In a divided last, the combination with a forepart and heel-part, of a link connection pivoted at its opposite ends in the respective last-parts, the forepart having at its rear end a wall extending obliquely rearwardly and downwardly to the bottom of the last, said wall, from approximately the 80 middle of the last, extending in a single uninterrupted plane to the bottom of the last, and the heel-part having a complementary flat surface abutting flat against the forepart when the last is in lengthened position, permitting the heel-part to slide continuously 85 rearward and downward on said wall until it reaches fully lengthened position, the upper end of the forepart from the top end of its said uninterrupted plane at approximately 90 said middle of the last being cut away at an angle to said plane, all constructed and operating to permit a swinging shortening movement of the heel-part for 95 disengagement from the counter portion of 100 a shoe, and a downward and continuously rearward sliding movement, when in the shoe, to fully lengthened position against the counter.

7. A divided last, having a heel-part provided at its front end with a secant wall extending downwardly and rearwardly in an oblique plane, and a forepart provided at its rear end with a secant wall extending downwardly from an intermediate point, in a 110 single uninterrupted plane the same as said wall of the heel-part and with a secant wall deflected obliquely forward and upward from said point at an angle from said plane, said point being located at a distance from 115 the bottom of the last permitting the heel-part to disengage from the counter of the shoe by a combined swinging-sliding, continuous-contact movement upon removal from the shoe, and connecting means for said 120 two last parts.

8. A divided last, having a heel-part provided at its front end with a secant plane wall extending downwardly and rearwardly in an oblique plane, and a forepart provided 125 at its rear end with a secant wall extending downwardly from an intermediate point, in the same uninterrupted plane as said wall of the heel-part and with a secant wall deflected obliquely forward and upward from 130

the same intermediate point at an angle from said plane, said point being located at a distance from the bottom of the last permitting the heel-part to disengage from the 5 counter of the shoe by a swinging movement about said point upon removal from the shoe, and a connecting plate between said last parts, with a slot and pin at one end in one of said last parts permitting the latter to remain in mutual contact throughout their entire collapsing and lengthening movements.

9. In a divided last, a heel-part and forepart severed from each other by a line of cut permitting the heel-part when in the 15 shoe to slide downwardly and rearwardly in substantial parallelism to itself at all points for engaging the counter portion of a shoe and to swing upwardly for leaving the counter portion of the shoe, connecting means for said two last parts, and a shouldered projection extending approximately vertically from the heel-part into the forepart for maintaining the last parts in alinement.

10. A divided last, having its forepart provided at its rear end with two transverse meeting secant faces at an angle to each other and both extending obliquely downward and continuously rearward toward the 25 heel end of the last, the lower of said two secant faces being steeper than the upper and extending in a single plane to the line of meeting the other face, and having its heel-part provided with an oblique secant face extending in a single plane throughout its entire area adapted to rest flat against the lower of said forepart faces when the last is

in lengthened position, and flat against the upper of said forepart faces when the last is in fully collapsed position within a shoe, and means permanently connecting said forepart and heel-part and permitting the heel-part to adjust its said secant face flat against the lower forepart face when the last is lengthened, and flat against the upper forepart face when the last is shortened, whereby 45 when the last is in said shortened position the said two abutting faces tend to aid in maintaining the last in position for receiving a shoe when being relasted.

11. A divided last, having its parts severed by an angular line of cut extending down from the crown of the last obliquely rearwardly, a single connecting link pivoted in the heel-part and also in the forepart approximately midway from the bottom to the 55 top of the last substantially in a horizontal plane when in last-lengthening position, the upper portion of said angular line of cut extending in a plane which is deflected forward from the plane of the contiguous part of said angular cut, said last-parts abutting flat 60 against each other in mutually sustaining engagement when in lengthened position and also when in shortened position.

In testimony whereof, I have signed my 65 name to this specification, in the presence of two subscribing witnesses.

EDWIN O. KRENTLER.
